METHOD OF AND APPARATUS FOR CONTROLLING THE FLOW OF LIQUID REFRIGERANT INTO AN EXPANSION SYSTEM

Thomas I. Potter, Portland, Oreg.

Application January 26, 1931, Serial No. 511,268

15 Claims. (Cl. 62—3)

This invention relates generally to mechanical refrigeration, and particularly to a method of and apparatus for controlling the flow of liquid refrigerant into an expansion system.

5 The main object of this invention is to provide a method of and apparatus for controlling the flow of liquid refrigerant into an expansion line, with special reference to small units in which the volume of refrigerant delivered to the evaporator at any one period is exceedingly small.

10 The second object is to provide a control system for refrigerating units which have a number of expansion elements, which control will function properly regardless of the location of the expansion elements or the relative heat pumping requirements thereof.

15 The third object is to provide a special form of expansion valve for use in connection with the control system and the practice of the method above referred to.

20 Before entering into a description of this invention it must be understood that little difficulty is experienced in controlling the flow of refrigerant from the high to the low pressure side of a system in large plants, due to the relatively large volume of refrigerant passing through the expansion valve, which renders unnecessary extremely accurate adjustments. The greatest difficulty experienced is with small plants, especially 25 those employing ammonia, in which the volume of the stream of refrigerant flowing through the valve is extremely small, and in which the difficulty of maintaining this small flow under varying conditions increases rapidly as the volume decreases. It is for this purpose that I employ a 30 large volume flow which is easy to control, but interrupt the flow for the purpose of decreasing the total amount of refrigerant delivered in a given amount of time. In other words, I deliver 35 the refrigerant to the expansion line in separate measured quantities—that is, in a pulsating or interrupted flow instead of in a very small stream whose regulation is very difficult to maintain.

40 These, and other objects, will become more apparent from the specification following as illustrated in the accompanying drawing, in which:

45 Fig. 1 is a diagrammatic view of the entire system.

50 Fig. 2 is a vertical section through an electrically operated expansion valve.

55 Fig. 3 is a section taken along the line 3—3 in Fig. 2.

Fig. 4 is a perspective view of the core element forming a part of the expansion valve.

Similar numbers of reference refer to similar parts throughout the several views.

Referring in detail to the drawing, in order to illustrate this invention there is shown a compressor unit 10 including the usual operating motor 11 and receiver 12. A number of cooling boxes 13, 14 and 15 are also shown which, for the sake of illustrating the invention, are shown independently of each other. Each of the cooling boxes 13, 14 and 15 is provided with an expansion coil 16 equipped with an electrically operated expansion valve 17. The lower side of each expansion valve 17 is connected by means of a pipe 18 to the receiver 12, while the upper end of each valve 17 connects to its respective coil 16. The 10 opposite side of each coil 16 is joined by means of a pipe 19 to a pressure controlled switch 20, such as are commonly employed in refrigerating systems.

On each expansion coil 16 is placed a frost line 20 control thermostatically operated switch 21. Each box 13, 14, and 15 is provided with a second control switch 22 which is operated by box temperatures. It will be understood that the boxes 13, 14 and 15 may vary in type from the 25 ordinary cooling box to show case or brine tank.

In the system there is also provided a motor 30 operated interrupter 23 whose function it is to interrupt the flow of current which may be flowing to any or all of the expansion valves 17. The primary circuit 24, which is shown in heavy lines, passes in series through the pressure controlled switch 20 and the motor 11, under the control of a manually operated switch 25. From the primary circuit 24 extends a pair of leads 26 to the motor 26a of the interrupter 23 and a rheostat 26b provides means for varying the speed of the motor and hence the frequency of interruptions. Across the primary circuit 24 is placed a transformer 27, one side of whose secondary coil is 35 connected to one side of each expansion valve by means of a wire 28. The second side of each expansion valve 17 is connected by means of a wire 29 to its respective frost line control switch 21. Each frost line control switch 21 is joined 40 by a wire 30 to its box and temperature control switch 22. Each box temperature control switch 22 is connected by means of a wire 31 to one side of the interrupter 23 whose opposite side is connected by means of a wire 32 to the transformer 27.

45 Referring in detail to the electrical valve, same will be seen to consist of an elongated tube 33 upon which is slidably mounted a solenoid coil 34 whose position on the tube 33 can be controlled 50 55

by means of a set screw 35. Within the tube 33 is placed a slidable core 36. The core 36 is provided with longitudinal grooves 37 on its sides between which are the communicating end 5 grooves 38 at its lower end. In its upper end is inserted a hardened pin 39. A plug 40 closes the lower end of the tube 33 and receives its respective end of the refrigerant pipe 19. In the top 10 of the tube 33 is inserted the valve body 41. Into its lower end is formed a seat 42 in which lies the tapered end 43 of the plug 44 which contains a spring 45 whose tension can be regulated by a threaded plug 46 within the upper end of the body 41. A cap 47 closes the upper end of the body 41 and receives its respective end of the pipe 19.

The operation of the device is as follows: Remembering that the operation of the compressor 10 is entirely under the control of the pressure 20 actuated switch 20 and that the compressor will be operated by the switch 20 whenever the pressure in the pipe 19 rises above a predetermined maximum, let us assume that the refrigerator is just being started, in which case all of the boxes 25 13, 14 and 15 are warm and their respective frost lines 16 are warm. In this event the switches 21 and 22 are closed, permitting current to flow from the wire 28 through the coil 34 to the wire 31. This flow of current is, however, interrupted by 30 the interrupter 23 causing an intermittent energizing of the coil 34 and a successive raising of the core 33. This causes the pin 39 to strike against the under side of the plug 44 raising it from its seat and permitting a quantity of refrigerant to enter its respective expansion coil 16.

This operation will be continually repeated until the temperature of the coil 16 falls sufficiently to open its respective frost line switch 21, thereby causing a cessation in the operation of 40 the expansion valve 17. However, as heat is drawn from the cooling box and absorbed by the coil 16 the switch 21 is again closed and the valve 17 again operated. However, when the temperature of the box drops sufficiently to open the 45 switch 22, this part of the circuit will not again be closed until both of the switches 21 and 22 are closed, by reason of the fact that there is too much heat at both of the locations.

While the operation at one of the cooling boxes 50 alone has been described it is identical when any number of boxes are employed, it being entirely immaterial as to the operating range of temperatures or the amount of heat pumped from any given position.

It can be seen that by this system it is possible 55 to accurately control the heat pumping action from a number of remote or separated points and to regulate the rate of heat absorption by varying the position of the coil 34 and the tension of the spring 45.

It will be noted that there are three possible 60 ways of varying the flow of refrigerant through the expansion valve aside from that obtained by variation in the pressure carried on the low pressure side of the system. The first is accomplished by varying the tension of the spring, the second the position of the coil with relation to the core and last the number and/or duration of interruptions imposed on the circuit. Not only may 65 these adjustments be made separately but with relation to each other, giving the utmost flexibility to the valve and making it possible to adapt same to a wide range of heat pumping requirements.

70 It will be seen from the foregoing that by this

method extremely small quantities of refrigerant can be liberated in a given amount of time with the greatest amount of certainty that the amounts delivered will not be objectionably affected by the presence of moisture or foreign substance, or 5 by changes in temperature or pressure within the related mechanisms.

I claim:

1. In a refrigerating machine, the combination of a condensing unit, and an expansion unit with 10 means for intermittently admitting liquid refrigerant from the high side to the low side so that the refrigerant will flow in a pulsating stream, together with means for varying the effective cross-section of the opening in the intermittently 15 operating means.

2. A method of controlling the flow of refrigerant into an expansion line consisting of establishing a pressure differential for the purpose of holding liquid refrigerant at a pressure over that 20 in said expansion line, then liberating a pulsating stream of refrigerant to the lower pressure zone, and then relating the pressure of the refrigerant to the volume of flow and frequency of 25 the pulsations in the manner to provide an aggregate delivery of the desired amount of refrigerant in a given period of time.

3. In a control for refrigerating systems, the combination of a pressure actuated motor controlling switch, an electrically operated expansion 30 valve adapted to liberate refrigerant into an expansion line, a temperature actuated switch adapted to be closed by a rise in temperature in said line and connected in series with said electrically operated expansion valve, and means for 35 interrupting the flow of current to said temperature actuated switch, said means comprising a compartment temperature switch adapted to be opened by a fall of temperature.

4. In a refrigerating system, the combination 40 of an electrically driven refrigerating unit including a refrigerant line with a pressure actuated switch in the low pressure side of said refrigerant line adapted to cause the operation of said unit during over-pressures in said low pressure 45 line, a cooling compartment associated with said refrigerating unit, an expansion coil in said compartment connected to said refrigerant line, an electrically operated expansion valve at the inlet end of said expansion coil, a frost line 50 control switch on said expansion coil, a compartment temperature switch in series with said frost line control switch, and a coil associated with said expansion valve in series with both of said temperature switches. 55

5. In a refrigerating system, the combination of a refrigerant line, means for maintaining condensed refrigerant in a portion of said line, an intermittently operated expansion valve through which the condensed refrigerant must pass, an electrical coil for operating said valve, an interrupter in the coil circuit, and a pair of temperature actuated switches in series with the coil circuit, one of said temperature switches operating under frost line temperatures and the other under box temperatures to the end that an over-temperature at both the frost line and in the box will cause an operation of the expansion valve and an under-temperature 65 at either the frost line or the box will stop the 70 operation of said valve.

6. In a refrigerating system having a plurality of heat pumping zones, the combination of an electrically operated compressor unit having a 75

- refrigerant line connected thereto, each of said zones having an independent expansion line provided with an electrically operated expansion valve, and a dual control for said expansion valve
- 5 consisting of a pair of temperature actuated switches in series with the operating mechanism of said valve, one of said temperature switches closing under rises in the frost line temperature and the other under rises in the box temperature.
- 10 7. In a refrigerating system, the combination of a pumping unit having a pressure actuated switch for controlling its operation and a plurality of cooling compartments from which heat may be drawn by said pumping unit, a pair of thermostatic switches in each compartment one of which is located near the frost line thereof and the other being disposed at a position for operation under compartment temperatures, separate expansion means between each compartment and the pumping unit, and electrically operated expansion means connected in series with said thermostatic switches for the purpose of stopping the operation of said expansion means when either of said thermostatic
- 15 switches opens the circuit due to a local drop in temperature and causing said expansion means to be operated when both of said thermostatic switches are closed by over-temperatures at their respective locations.
- 20 8. In a refrigerating machine the combination of a condensing unit, an expansion unit, a refrigerant line connecting said units in a closed cycle, an expansion valve in the line for admitting refrigerant from the condensing unit
- 25 into the expansion unit, an actuator for rhythmically opening and closing said valve at a predetermined frequency so as to pulsate the flow of refrigerant into the expansion unit, and means for regulating the extent of opening of the valve.
- 30 9. In a refrigerating machine the combination of a condensing unit, an expansion unit, a refrigerant line connecting said units in a closed cycle, an expansion valve in the line for admitting refrigerant from the condensing unit
- 35 into the expansion unit, an actuator for rhythmically opening and closing said valve at a predetermined frequency so as to pulsate the flow of refrigerant into the expansion unit, and means for regulating the duration of openings of the
- 40 valve during such pulsating flow.
- 45 10. In a refrigerating machine the combination of a condensing unit, an expansion unit, a refrigerant line for supplying a stream of liquid refrigerant to said expansion unit, means for controlling periods of flow of the refrigerant
- 50 into said expansion unit, an interrupter for sub-dividing the flow during each period, and means for varying the frequency of the interrupter.
- 55 11. In a refrigerating machine the combination of a condensing unit, an expansion unit, a refrigerant line for supplying a stream of liquid refrigerant to said expansion unit, means for controlling periods of flow of the refrigerant into said expansion unit, an interrupter for sub-dividing the flow during each period into a series of slugs of refrigerant, and means for varying the time intervals between successive slugs.
12. In a refrigerating machine the combination of a condensing unit, an expansion unit, a refrigerant line for supplying a stream of liquid refrigerant to said expansion unit, means for controlling periods of flow of the refrigerant into said expansion unit, an interrupter for sub-dividing the flow during each period into a series of slugs of refrigerant, and means for varying the volume of each slug and the time interval between successive slugs.
13. In a refrigerating machine the combination of a condensing unit, a pair of expansion units, a supply of liquid refrigerant, means for rhythmically connecting and disconnecting each expansion unit directly to and from said supply so as to provide a pulsating flow into each expansion unit, and means for varying the frequency of pulsation of each delivery so as to provide an aggregate delivery into each expansion unit of a desired amount of refrigerant in any given period of time.
14. In a refrigerating machine the combination of a condensing unit, an expansion unit, a supply of liquid refrigerant, means for rhythmically connecting and disconnecting the expansion unit directly to and from said supply so as to provide a pulsating flow into the expansion unit, and means for varying the frequency of the pulsations so as to provide an aggregate delivery into the expansion unit of a desired amount of refrigerant in any given period of time.
15. In a refrigerating machine, the combination of a condensing unit, an expansion unit, and means for intermittently admitting liquid refrigerant from the high side to the low side so that the refrigerant will flow in a pulsating stream, said means comprising an admission valve opening from the high side directly into the low side and adjustable operating means for said valve controlling the extent to which the valve is opened at each operation thereof.

THOMAS I. POTTER. 55
